Patented Feb. 6, 1917.

UNITED STATES PATENT OFFICE.

FREDERICK S. USHER, OF INDIANA HARBOR, INDIANA.

EGG AND CREAM WHIPPER.

1,214,975.

Specification of Letters Patent.

Patented Feb. 6, 1917.

Application filed April 6, 1916. Serial No. 89,422.

To all whom it may concern:

Be it known that I, FREDERICK STONE USHER, a citizen of the United States, residing at Indiana Harbor, in the county of 5 Lake and State of Indiana, have invented certain new and useful Improvements in Egg and Cream Whippers, of which the following is a specification.

This invention relates to improvements in 10 egg beaters, cream whippers, and similar devices, and has for one of its objects to improve the construction and increase the efficiency and utility of devices of this character.

15 Another object of the invention is to provide a simply constructed device whereby a two-fold action is produced upon the cream or other product without materially increasing the force necessary to operate the device.

20 With these and other objects in view, the invention consists in certain novel features of construction, as hereinafter shown and described and then specifically pointed out in the claims; and in the drawings illustrative of the preferred embodiment of the invention—

Figure 1 is a side elevation of the improved device;

Fig. 2 is a transverse section on the line 30 2—2 of Fig. 1;

Fig. 3 is a perspective view from beneath of the combined transverse connecting member and support for the frame and operating mechanism;

35 Figs. 4 and 5 are views of the blanks from which the member shown in Fig. 3 is constructed.

40 Corresponding and like parts are referred to in the following description and indicated in all the views of the drawings by the same reference characters.

45 The improved device comprises in general a supporting frame including spaced sides, a connecting device at the upper end of the frame, beater devices operating within the frame, and means for actuating the beater devices.

50 The frame portion of the device is constructed from two sections of material, preferably heavy wire twisted together, as shown at 10, near their ends with the shorter portions bent first vertically for a short distance, as shown at 11—12, and thence curved in opposite directions, as shown at 13—14. 55 The longer portions of the frame members are first curved in opposite directions, as

represented at 15—16, and extending substantially in parallel relations to the portions 13—14, and thence directed vertically in parallel relations, as shown at 17—18, the 60 portions 17—18 forming the sides of the supporting frame.

At their upper ends the side members 17—18 are united by a transverse connecting device initially formed from plates of sheet 65 metal and cut in the form shown in Figs. 4 and 5. The portion illustrated in Fig. 5 includes a central body portion 19 which forms the top of the connecting device, laterally directed portions 20 which form the sides of 70 the connecting device and end portions 21 which form the ends of the connecting device. The end portions 21 are of greater length than the lateral portions 20, as shown in Fig. 5. To construct the connecting device the side portions 20 are bent at right angles to the body 19 along the dotted lines 22 and the edges of the portions 20 likewise bent at right angles to the portions 20 along the dotted lines 23 to form guide ledges or 80 flanges 24, as shown in Fig. 3. The terminals 21 are first bent at right angles to the body 19 along the dotted lines 25 and the outer portions of the ends bent at right angles along the dotted lines 26 and the terminals of the ends bent over along the dotted lines 27 to form channels 28, as indicated in 85 Fig. 3. By this means the portions which are bent at right angles along the lines 26 extend in parallel relation with the longitudinal plane of the connecting device so that the turned over portions 24 and 28 serve as ribs to support a base plate 29. When thus assembled a box-like structure is produced with projections at the ends, as shown 90 in Figs. 1 and 3. The base 29 and the end extensions of the connecting member are pierced to receive the upper ends of the side members 17—18 of the frame, the terminals of the side members being bent or clenched 100 over the projecting portions of the connecting device, as illustrated at 30 in Fig. 1. By this means the frame members coact with the twisted portions 10 and the connecting device to produce a rigid frame or support 105 including the curved portions 13—14 and 15—16.

The beater mechanism of the improved device comprises coacting reversely twisted members 31—32 pivoted at their upper ends, 110 as represented at 33—34 in the base portion 29 of the connecting member, and ex-

tending between the side portions 17-18 and in parallel relation thereto and bent into hoop-like terminals 35-36 at their lower ends. The members 35-36 form the 5 beaters of the improved device and are mounted to rotate upon the vertical portions 11-12 of the frame, as shown in Fig. 1. The beater member 35 thus rotates between the inner frame portion 13 and the outer 10 frame portion 15, while the beater member 36 rotates between the inner frame portion 14 and the outer frame portion 16. The members 31-32 being twisted in opposite directions will likewise rotate in opposite 15 directions, as hereafter explained, and thus cause the sides of the beater members to alternately pass between the spaced frame portions 13-15 and 14-16. The beater members 35-36 are so mounted and operated that they alternately rotate one within the other without coming in contact, as will be obvious.

Movable vertically through suitable apertures in the top 19 and the base 29 of the 25 connecting device is an operating rod including a main body portion 37 terminating in a hand grip 38 at the upper end and bent into lateral loops 39-40 at the lower ends, the loops being flat and engaging 30 around the twisted members 31-32, as illustrated in Fig. 2. The loops 39-40 fit with sufficient looseness around the twisted members to cause the loops to rapidly rotate the twisted members when the rod is moved vertically. Thus when the rod is moved downwardly the twisted member 31 will be moved in one direction and the twisted member 32 will be moved in the opposite direction, and then when the rod is moved upwardly the 35 twisted members will be reversed in movement, as will be obvious. A spring 41 is connected at its upper end to the base member 29 of the connecting device and at its lower end to the transverse portion of the rod, so that when the rod is moved downwardly the spring will be distended and when the rod is released the spring by its reaction will return the loops 39-40, together with the rod, to their upper position. 40 The member 31 and the hoop-like beater member 35 are constructed from a sheet of metal of suitable width and the terminal of the beater 35 soldered, brazed, electrically welded, or otherwise attached, as illustrated 45 at 43, while the twisted member 32 and the beater 36 are in one single piece with the terminal suitably attached, as shown at 44.

The members 13-15 coact with the beater 35, while the similar members 14-16 coact 50 with the beater 36, the portions 13-14 materially increasing the action and correspondingly decreasing the time required to produce the desired results.

A stop 45 is arranged upon the rod 37 to 55 engage the connecting member to limit its

downward movement, the stop being preferably formed by extending the terminal of the rod 37 and twisting it around the body of the rod, as shown in Fig. 1. By this means the hand grip 38 is limited in its 70 downward movement to prevent the fingers of the operator from being pinched against the connecting member. The stop also prevents the spring 41 being unduly stretched, and prevents the members 40 from striking 75 the joints 43 and 44.

The improved device is simple in construction, is constructed wholly of metal and is strong and durable and operates effectively for the purposes described.

Having thus described the invention, what is claimed as new is:

1. In a device of the class described, a hoop shaped beater mounted for rotation, and a frame including an outer member and 85 an inner member, said inner member extending through one wall of the hoop shaped beater and forming a bearing therefor whereby the sides of the hoop shaped beater operate alternately between the outer and 90 inner frame members.

2. In a device of the class described, a hoop shaped beaters mounted for rotation side by side, a frame including oppositely curving outer portions, means for connecting the beaters at their lower sides, inner frame members each including an upwardly directed vertical lower portion rising from the frame members at the terminals of the connecting means and upon which the beaters are rotatable, said inner frame members extending into the beaters and between which and the outer frame members the beaters alternately rotate.

3. In a device of the class described, a frame with the upper portion formed of sides spaced apart and oppositely curving lower portions united at their lower ends, inner frame members directed upwardly from the outer frame members, a connecting device at the upper ends of said outer frame members, oppositely twisted members pivoted at their upper ends in said connecting device and provided with hoop shaped beaters at their lower ends mounted for rotation upon the vertical bearings of the inner frame members and operating alternately between the oppositely curving frame portions and the inner frame members, a slide member 110 engaging said twisted members, and a rod 115 movable through said connecting device and connected to said slide member.

4. In a device of the class described, a frame formed of two sections of wire twisted together to unite them near one end with 125 the shorter untwisted portions extending vertically to form bearings and thence curved in opposite directions and the longer untwisted portions curved in opposite directions in parallel relation to the shorter 130

curved portions and thence extended for the remainder of the lengths in parallel relation to each other, a connecting device at the free ends of the last-mentioned parallel portions, oppositely twisted members pivoted at their upper ends in said connecting device and provided with hoop shaped beaters at their lower ends mounted for rotation on the vertically extending bearings of the shorter curved portions and alternately operating between the oppositely curved frame portions, a slide member engaging said twisted members, and a rod movable through said connecting device and connected to said slide member.

5. In a device of the class described, a connecting device comprising a sheet metal body having laterally extending sides and longitudinally extending ends, the sides and 20 portions of the ends bent at right angles to the body and the outer portions of the ends bent into parallel relation to the body, a base member held by its ends and sides by the turned over sides and ends, a frame having the upper portions of its sides spaced apart and connected to the extended ends of the connecting device, oppositely twisted members pivoted at their upper ends in the 25 base of said connecting device and with beaters at their outer ends, and coacting with the frame members, a slide member en-

gaging said twisted members, and a rod movable through said connecting device and connected to said slide member.

6. In a device of the class described, a 35 frame formed of two sections of wire twisted together to unite them near one end with the shorter untwisted portions extending vertically to form bearings and thence curved in opposite directions and the longer untwisted 40 portions curved in opposite directions and extending in parallel relation to the shorter curved portions, hoop-shaped beaters mounted for rotation on the bearings of the shorter curved portions and alternately 45 operating between the oppositely curved frame portions, and means for rotating said beater members.

7. In a device of the class described, a frame including sides spaced apart, a connecting device at the upper ends of said frame sides, oppositely twisted members pivoted at their upper ends in said connecting device and provided with beater devices, a slide member engaging said twisted members, a rod movable through said connecting device and connected to said slide member, and a stop carried by said rod externally of the connecting device to limit the 55 inward movement of the slide device. 60

In testimony whereof I affix my signature.
FREDERICK S. USHER. [L. S.]
